UNITED STATES PATENT OFFICE.

GEORGE R. MARGETTS, OF CHICAGO, ILLINOIS, ASSIGNOR OF ONE-HALF TO JOHN P. KEARY, OF CHICAGO, ILLINOIS.

SPOON.

1,273,642.

Specification of Letters Patent. Patented July 23, 1918.

Application filed February 13, 1918. Serial No. 216,929.

To all whom it may concern:

Be it known that I, GEORGE R. MARGETTS, a citizen of the United States, residing at Chicago, Cook county, Illinois, have invented 5 certain new and useful Improvements in Spoons, of which the following is a specification.

The present invention has to do with improvements in spoons, and has particular 10 reference to improvements in what I shall term medical spoons. While as a matter of convenience in designation or description, the spoon of the present invention may be described as a medical spoon, still it will 15 be understood that by such description, I do not in any way limit the field of usefulness or application of the invention to other different classes of service.

A medical spoon should be so constructed 20 as to be sanitary and cleanly to the highest possible degree, and for these purposes, it is desirable that the spoon should be so constructed that its bowl will not at any time in its ordinary use come into contact with 25 the table or other article of furniture on which the spoon may rest.

One of the objects of the invention is to 30 so construct the spoon as to accomplish this result. As a matter of convenience, a medical spoon should be so constructed that it will stand upright on the table or other article of furniture, so that it will carry medicine and the like without spilling. Another object of the invention is to so construct the spoon that this result will be 35 accomplished.

Still another object of the invention is to 40 so weight or balance the spoon that it will have a tendency at all times to right itself or restore itself to the upright or standing position. This will insure that the bowl of 45 the spoon will only come into contact with a table or other article of furniture momentarily in case the spoon should be dropped or thrown onto the supporting surface.

Other objects and uses of the invention will appear from a detailed description of the same which consists in the features of construction and combination of parts hereinafter described and claimed.

Referring to the drawing:

Figure 1 shows a plan view of a spoon embodying the features of my invention;

Fig. 2 shows a longitudinal vertical sec-

tion taken on the line 2—2 of Fig. 1, looking in the direction of the arrows; and

Fig. 3 shows a front end view of the spoon of Figs. 1 and 2.

The spoon of my invention includes a bowl 4 and a handle 5. These portions are ordinarily made as an integral or unitary piece, and manifestly the spoon may be cast, or it may be stamped out, or drop-forged, or made in any other suitable manner.

The handle 5 comprises a rearwardly extending relatively narrow neck or tong portion 6, the rear end of which is turned down and connected to the forwardly extending base or supporting portion 7. This portion 7 has its forward end 8 terminating at a position approximately under the lower portion of the bowl so as to give ample support for the bowl.

Examination of Figs. 1 and 3 shows that the base portion 7 is of substantial width. Fig. 2 also shows this portion of substantial thickness as compared to the remaining portions of the spoon. On account of these facts, the spoon is practically self-righting—that is, the center of gravity of the entire article is brought so low down that the spoon will right itself from almost any position which it may find on striking a table or floor.

Fig. 1 shows that both the front and rear ends of the base portion 7 are of substantially the full width of such base portion, and, therefore, afford a maximum degree of self-righting tendency with a minimum weight of the base portion.

Figs. 2 and 3 also reveal the fact that the bowl is at all times supported entirely clear of the upper surface 9 of a table or other article on which the spoon is supported. Fig. 2 also shows that the central part of the base portion 10 is bowed up slightly, so that the points of contact are at the front and rear ends of said base portion.

While I have herein shown and described only a single embodiment of the features of my invention, still it will be understood that I do not limit myself to the said embodiment except as I may do so in the claims.

I claim:

1. As a new article of manufacture, a spoon of the class described, comprising an integral structure including a bowl, a rela-

tively narrow handle rearwardly extending from said bowl and having its rear end turned downwardly, and having a forwardly extending relatively wide base portion terminating in a point of contact beneath the central portion of the bowl, said base portion being in spaced relation with respect to the lower surface of the bowl, and said base portion being relatively heavy as compared to the bowl to thereby produce a self-righting tendency, and the downwardly extending portion of the handle being so formed as to support the bottom of the bowl clear of a surface on which the spoon is supported, substantially as described.

2. As a new article of manufacture, a spoon of the class described, comprising a rigid structure including a bowl, a rearwardly and downwardly extending relatively narrow handle connected to the bowl, a forwardly extending relatively wide base portion connected to said handle, and having a point of support beneath the bowl,

said base portion being in spaced relation with respect to the lower surface of the bowl, and the base portion being relatively heavy to thereby produce a self-righting tendency, and the handle portion being so formed as to support the bowl with its lower surface clear of a surface on which the spoon is supported, substantially as described.

3. As a new article of manufacture, a spoon of the class described, comprising a bowl, a rearwardly and downwardly extending handle connected to the same, a forwardly extending relatively wide base portion connected to said handle, and having a point of support beneath the bowl, said base portion being in spaced relation with respect to the bowl, and the handle being so formed that the lower surface of the bowl is supported clear of a surface on which the base portion is resting, substantially as described.

GEORGE R. MARGETTS.
